UNITED STATES PATENT OFFICE.

HARVEY C. MUMMERT, OF HOLLIS, AND JOSEPH F. MEADE, OF FREEPORT, NEW YORK, ASSIGNEES, BY MESNE ASSIGNMENTS, TO CURTISS AEROPLANE AND MOTOR COMPANY, INC., OF GARDEN CITY, NEW YORK, A CORPORATION OF NEW YORK.

AEROPLANE RADIATOR.

Application filed November 29, 1922. Serial No. 604,076.

Our invention relates to aeroplane radiators and more particularly to improvements in wing radiators of the skin or surface type, i. e., a type recently developed by the Curtiss Aeroplane & Motor Corporation, and disclosed in its original form in application Serial No. 470,186, filed May 16th, 1921.

An object of the invention is to construct the radiator in parts or sections that the separate parts or sections may be separately assembled or removed to the end that installation, repair, and replacement can be easily and quickly accomplished.

A further object of the invention is the construction of the radiator parts or sections in such a manner that one of said parts or sections is adapted to provide an outer covering for a given portion of the wing or aerofoil in connection with which it is used, whereas another section or other sections are adapted to provide an outer covering for the remaining part or portion of said wing or aerofoil; said radiator parts or sections being separately removable and so organized as to collectively define a hollow radiator through the hollow of which at least a portion of the framework of the wing or aerofoil is adapted to extend substantially uninterruptedly.

A still further object of the invention is the provision of headers, each header comprising separate header sections, one of which sections, in each instance, is interconnected with one of the header sections of the other of said headers, the interconnecting portion being preferably cellular and so disposed upon the exterior of the wing or aerofoil as to provide the necessary cooling surface.

Other objects of the invention, such for instance as the specific disposition of the header sections, the arrangement of the inlet and outlet water passages respectively to and from the headers, the header formation in cross section, etc., will be hereinafter more fully explained.

In the drawings, wherein like reference characters designate like or corresponding parts:-

Figure 1 is a plan view of a radiator constructed in accordance with the teachings of the present invention;

Figure 2 is an enlarged transverse sectional view of the radiator with its center portion broken away;

Figure 3 is a detail sectional view of a portion of the forward header showing the manner in which the header sections are joined; and,

Figure 4 is a detail sectional view of the rear header showing the manner in which the outlet water passage is fastened in place.

As explained in the original application above referred to, wing radiators of the skin or surface type are especially desirable in view of the lack of head resistance which radiators of this particular type offer to forward flight. In the embodiment of the invention selected for illustration the radiator comprises separate radiator sections 10 placed edge to edge both on the top surface and on the under surface of the wing. Thus organized, it is apparent that the wing, designated at 11, provides the necessary radiator support. At its forward end the radiator is provided with a forward header 12 and at its rear end is provided with a rear header 13, the former being so related to the wing 11 as to constitute the nose portion thereof, and the latter so related to the wing 11 as to constitute the trailing edge portion thereof. Both headers 12 and 13 are of gradually decreasing cross sectional area from end to end, the forward header 12 at its larger end being provided with an inlet water passageway 14 and the header 13 at its larger end being provided with an outlet water passageway 15. Such difference in cross sectional area of the radiator headers is instrumental in obtaining a more uniform distribution of the cooling agent in its circulation through the various radiator parts.

The forward header 12 of the radiator comprises separate header sections 16 and 17, whereas the rear header 13 comprises separate header sections 18 and 19. Each header section is formed of sheet metal bent as indicated in Figure 2 to provide a plurality of securing flanges 20, the flanges 20 of the header sections 16 and 17 being adapted to overlap, as are also the flanges 20 of the header sections 18 and 19. Collectively the flanges 20 provide a means for fastening the header sections, together,

screws 21 (see Fig. 4) being used as the fastening means. To reinforce the flanges 20 lugs 22 are provided at the points where the screws 21 are disposed.

- 5 The radiator sections 10 which bear against the opposite faces of the wing 11 afford the necessary interconnections between the radiator headers. The sections 10 which bear on the top surface of the wing 10 interconnect the forward header section 16 with the rear header section 19, whereas the sections 10 which bear on the under surface of the wing interconnect the forward header section 17 with the rear header section 18, 15 and since the interconnecting portions are in each instance integral with the header sections which they connect, obviously the radiator considered in its entirety, may be said to comprise separate radiator parts. 20 The headers 12 and 13 are open ended at their larger ends and provided with flanges 23 for the attachment of the water pipes 14 and 15, said pipes being likewise flanged as indicated at 24 and riveted as at 25 to the flanges 23 which they abut. Between the flanges 23 and 24 suitable packing 26 is interposed.

It is obvious from the foregoing that the radiator parts are each so organized as to provide an outer covering for a portion only of the wing. It is further evident that the radiator parts may be separately removed and replaced without correspondingly removing or in any way effecting the remaining radiator part or parts. If desired, instead of interconnecting the header sections 16 and 19 as indicated in Figure 2 the header sections 16 and 18 may be interconnected, in which event the header sections 17 and 19 30 should be interconnected instead of the header sections 17 and 18 as shown. Preferably the cooling surface or interconnecting portions are constructed in accordance with methods heretofore explained in applications now on file.

While we have described our invention in detail in its present preferred embodiment, it will be obvious to those skilled in the art after understanding our invention, that various changes and modifications may be made therein without departing from the spirit or scope thereof. We aim in the appended claims to cover all such modifications and changes.

What we claim is:

1. An aeroplane radiator comprising separate headers, each header in turn comprising separate substantially parallel header sections, a connecting portion between one header section of each header, and a connecting portion between the other header section of each header, the connecting portions, in each instance, being separately formed and so organized as to jointly provide the radiator cooling surface.

2. An aeroplane radiator comprising separate headers, each header in turn comprising separate substantially parallel header sections, a connecting portion between one header section of each header, a connecting portion between the other header section of each header, the connecting portions in each instance being separately formed and so organized as to jointly provide the radiator cooling surface, an inlet water passage common to the header sections of one of said headers, and an outlet water passage common to the header sections of the other of said headers.

3. An aeroplane radiator comprising longitudinally divided headers of gradually decreasing cross sectional area from end to end, connections between the divided headers so constructed as to provide the necessary cooling surface, an inlet water passage common to the divisions comprising one of said headers, and an outlet water passage common to the divisions comprising the other of said headers, said water passages in each instance being open to the headers at 90 their respective larger ends.

4. An aeroplane radiator comprising, in combination with an aerofoil, separate radiator headers, each header comprising separate substantially parallel header sections arranged to extend longitudinally of the aerofoil, a connecting portion between one header section of each header arranged to provide an outer covering for a portion, at least, of the top surface of the aerofoil, a connecting portion between the other header sections of each header arranged to provide an outer covering for a portion, at least, of the under surface of the aerofoil, and said connecting portions jointly providing the 10 radiator cooling surface.

5. An aeroplane radiator comprising, in combination with an aerofoil, a radiator section comprising separate header portions and a connecting portion, said connecting portion being fastened in place upon the aerofoil to provide an outer covering for a portion, at least, of the top surface thereof, a second radiator section comprising separate header portions and a connecting portion in which the latter connecting portion is fastened in place upon the aerofoil to provide therefor an outer covering for a portion, at least, of the under surface of the aerofoil, the header portions of each radiator section being extended lengthwise the aerofoil and contiguous, an inlet water passage common to the corresponding header portions of said two radiator sections, and an outlet water passage common to the two remaining 1 header portions thereof.

In testimony whereof they hereunto affix their signatures.

HARVEY C. MUMMERT.
JOSEPH F. MEADE,
